(57) **CLAIM**

The ornamental design for a sensor cap, as shown and described.

DESCRIPTION

FIG. 1 is a right upper front perspective view of a sensor cap. FIG. 2 is a top view of the sensor cap as shown in FIG. 1 with the right side of the sensor cap shown in the bottom of the figure.

FIG. 3 is a bottom view of the sensor cap as shown in FIG. 1 with the right side of the sensor cap shown in the top of the figure.

FIG. 4 is a left view of the sensor cap as shown in FIG. 1. FIG. 5 is a right view of the sensor cap as shown in FIG. 1; and,

FIG. 6 is a rear view of the sensor cap as shown in FIG. 1, wherein the front view is a mirror image.

The broken lines in the drawings represent a sensor cap and form no part of the claimed design.
